UNITED STATES PATENT OFFICE.

JOHN C. CROMWELL, OF CLEVELAND, OHIO.

WHEEL-FORGING MACHINE.

1,115,786.

Specification of Letters Patent. Patented Nov. 3, 1914.

Application filed June 30, 1910. Serial No. 569,819.

To all whom it may concern:

Be it known that I, JOHN C. CROMWELL, of Cleveland, in the county of Cuyahoga and State of Ohio, have invented a new and useful Wheel-Forging Machine, of which the following is a full, clear, and exact description, reference being had to the accompanying drawings, forming part of this specification, in which—

10 Figure 1 is a side elevation partly in section showing one form of my improved machine for forging wheels or circular articles. Fig. 2 is a view similar to Fig. 1, showing a modified form of the invention, 15 and Figs. 3 and 4 are cross-sections on the lines III—III and IV—IV respectively of Fig. 2.

15 My invention relates to the roller-forging of circular articles, such as steel car wheels. 20 The object of the invention is to provide an improved machine of simple and strong construction by which a disk or cheese-shaped blank of hot steel or other desirable metal may be forged to the desired shape 25 in an inclosing die or dies.

In the preferred forms of my invention, the disk or cheese-shaped blank is thicker and of less diameter than the finished wheel. The blank is preferably perforated, and 30 either provided with a mandrel before insertion into the roller-forming machine, or is slipped upon a centering mandrel, which may be a part of the machine, either fixed to or removably attached to the die or roller 35 carrier.

40 In the drawings, 2 represents a circular die, which is preferably in one piece, and is provided at its top with the die cavity of the shape of the article to be formed, in this case, a steel car wheel. This die is removably secured to the enlarged head 3 of a hydraulic plunger 4, movable within a hydraulic cylinder 5, which is revolvably mounted in a marine thrust bearing, indicated at 5*. The marine thrust bearing is 45 formed between the hydraulic cylinder 5 and a hollow stationary cylindrical casing 6, which is bolted or otherwise secured to the housing 7.

50 8 indicates a portion of the water-cooling cavity or cavities within the hollow casing. The head 3 of the plunger is provided with the outwardly projecting lugs 9, which move within suitable slots in an outer outwardly 55 projecting casing portion 10 of the hydraulic cylinder 5, thus giving practically a

crab-clutch connection between the plunger head and the revoluble cylinder. To the lower end of the cylinder is keyed or otherwise secured a bevel wheel 11, meshing with 60 bevel pinion 12, mounted on shaft 13, extending through suitable bearings in the housing.

One portion of the housing is extended 65 upwardly, as shown at 14, to carry one of the bearings for a large shaft 15, carrying at its inner end an overhung forging roller 16. This forging roller is of the proper shape desired for one face of the car wheel or other article, and preferably extends from 70 the removable mandrel 17 to the blank out to and over the die. The dividing line between the roller and the die is preferably at the largest portion of the wheel, namely, 75 at the edge of its flange in the case of a car wheel, so that the wheel may be readily removed from the die when the rolling operation is completed. The mandrel 17 is preferably provided with a reduced lower portion which seats in a corresponding central recess in the die. The shaft 15 is preferably provided with one or more additional bearings, one of which is indicated at 18, 80 and is preferably positively driven by gear connections.

In the operation of the machine, the plunger being lowered, the wheel blank is placed 85 in the die, and if the mandrel is in the blank its projecting end is slipped into the central cavity in the die. If the mandrel is present 90 in the die, the wheel blank is slipped over it. Positive rotation is then imparted to the hydraulic cylinder and to the roller 16. At the same time fluid is admitted to the 95 hydraulic cylinder, thus forcing the wheel blank upwardly against the forming roller, which roller forges the metal into the shape of the wheel. The surplus metal in the blank, if any, will be forced into fins at either or both edges of the forming roller. 100 The roller may overlap the mandrel if desired. The die is then lowered by exhausting the fluid from the hydraulic cylinder, the formed wheel is removed, another blank inserted, and the operation repeated. 105

Instead of driving the roller by positive gear connections with its carrying shaft, I may drive the roller or rollers in other ways. Thus, in Figs. 2, 3 and 4, I show the die, 110 hydraulic plunger and cylinder, marine thrust bearing, casing and driving gear, substantially the same as in Fig. 1. In this

case, however, both side portions of the housing are extended upwardly and provided with the upper cross-pediment 19, which is provided with a hollow casing 20 5 secured thereto and having a marine thrust bearing with a hollow revoluble shaft 21. To the upper end of this shaft is secured a bevel wheel 22 intermeshing with bevel pinion 23 on the driving shaft 24. The lower 10 end of the hollow shaft 21 is provided with a head 25, to which is secured a plate or disk 26, which I term the pressure disk, for the forming rollers 16^a. The face of this pressure plate which contacts with the rollers, is provided with annular grooves which 15 fit and conform to the contour of the rollers. I have shown two of these rollers mounted on a transverse shaft 27, as shown in Fig. 4, each roller being made up of several independently rotatable disks to more effectually 20 provide for the differences in speed, owing to their being at different distances from the center of the path of rotation. The ends of the shaft 27 are mounted in flattened 25 parallel portions of a carrying ring 28, which is carried on arc-shaped hangers 29 secured at opposite sides of the head 25. The vertical recesses in these hangers are of sufficient height to allow some vertical movement 30 of the rollers and carrying shaft, and in operation the rollers are backed up by the pressure plate, the pressure on which is carried by the marine bearing between the upper driving shaft and casing. A central spacer may be inserted between the two 35 rollers, and nuts are provided at the outer ends of the shafts to hold the disks of each roller in proper position, while allowing relative movement between the forming 40 disks of the rollers.

In the operation of this machine, the blank of the mandrel is dropped into the die and the hydraulic plunger is forced upwardly, while both the hydraulic cylinder and the upper 45 hollow shaft 21 are positively rotated, in opposite directions. As the hot metal blank contacts with the rollers 16^a, they will be pushed upwardly slightly against their 50 backing or pressure plate, and will rotate thereon within the annular grooves in which they fit. They are, therefore, not driven merely by friction with the blank, but are also driven by the rotation over them of the 55 pressure or backing plate within which they fit.

In any or all the forms of my invention, water is preferably supplied, preferably in the form of a spray or stream directly upon either the article or the rollers. I have indicated a pipe for this purpose at 34, but the water may be supplied in any desirable 60 way.

The advantages of my invention will be obvious to those skilled in the art. A simple strong and effective form of apparatus 65

is provided by which wheels may be roller-forged at one operation, if desired, from the blank. The blank may be produced by suitably cross-shearing steel ingots to produce a series of disks, or in any other desirable way. The die and the rollers both being driven, the operation is rapid and effective, and owing to rollers being used, the pressure on the blank is exerted to a considerable depth therein. 70

It will readily be understood by those familiar with the art that various changes within the scope of the appended claims may be made in the details of the construction of the various parts, and particularly 75 the actuating mechanism for rotating the forming rollers relatively to the die. It will also be understood that the various parts can be moved relative to each other in various manners, without departing from the 80 spirit and scope of my invention, as defined in the appended claims.

I claim:

1. In a roller-forging press for substantially circular articles, an inclosing die, a 90 roller having a peripheral forming surface, actuating connections for positively rotating said roller, and means for effecting relative bodily movement between the roller and die; substantially as described. 95

2. In a roller-forging press for substantially circular articles, a roller having a peripheral forming surface, connections for positively rotating the roller, an annular die, connections for causing relative bodily 100 movement between the roller and die, and connections for causing a relative rotary movement between the die and roller; substantially as described.

3. In a roller-forging press for substantially circular articles, a forming roller having a peripheral forming surface, an inclosing die arranged to rotate on a central axis, actuating connections for positively rotating said roller and die, and means for effecting relative bodily movement between the roller and die; substantially as described. 105

4. In a roller-forging press for substantially circular articles, a roller having a peripheral forming surface, arranged to shape 115 at least one face of the article, an inclosing die arranged to shape another part of the article, means arranged to cause relative bodily movement between the roller and die, and actuating connections for positively rotating the die and roller; substantially as described. 120

5. In a roller-forging press, a roller having a peripheral forming surface arranged to shape a portion of the article, an inclosing die arranged to rotate on a central axis, hydraulic means arranged to cause relative bodily movement between the die and roller, and actuating connections for positively rotating said roller; substantially as described. 125

6. In a roller-forging press, in inclosing die, a roller having a peripheral forming surface coating therewith, connections arranged to positively rotate said roller, and means for effecting relative bodily movement between the roller and die; substantially as described. 30
7. In a roller-forging press, an inclosing die, a roller having a peripheral forming surface coating therewith, actuating connections for positively rotating said roller and means for positively moving the die bodily toward the roller during rotation thereof; substantially as described. 35
- 10 8. In a roller forging press, an inclosing die, a carrier therefor, means for rotating the carrier, a roller having a peripheral forming surface coating with the die, connections arranged to positively drive the 40 roller, and means for effecting relative bodily movement between the roller and the die carrier; substantially as described. 50
- 15 9. In roller-forging apparatus, a forming die mounted on the movable member of a hydraulic motor, connections for rotating both members of the motor, a forming roller having a peripheral forming surface coating with the die, and connections ar- 45

- ranged to positively rotate said forming roller; substantially as described.
10. In roller-forging apparatus, a motor having a reciprocating member, a die carried by said member, means for rotating the member and die, a forming roller coating with the die, and means for positively rotating said roller; substantially as described.
11. In the roller-forging of substantially circular articles, the steps consisting of inclosing the blank within a die, applying the periphery of the forming roller to the blank, 40 positively rotating the roller and causing a relative bodily movement between the roller and die; substantially as described.
12. In the roller-forging of substantially circular articles, the steps consisting of inclosing the blank within a die, applying a forming roller to the blank, positively rotating the roller and die, and effecting a bodily movement between the roller and die; substantially as described.
- In testimony whereof, I have hereunto set my hand.
